UNITED STATES PATENT OFFICE.

THOMAS W. PATTERSON, OF KINGMAN, KANSAS.

MACHINE FOR HANDLING HEADED GRAIN.

1,250,640.

Specification of Letters Patent. Patented Dec. 18, 1917.

Application filed August 25, 1916. Serial No. 116,895.

To all whom it may concern:

Be it known that I, THOMAS W. PATTERSON, a citizen of the United States, residing at Kingman, in the county of Kingman and 5 State of Kansas, have invented new and useful Improvements in Machines for Handling Headed Grain, of which the following is a specification.

This invention relates to devices for handling headed grain, and it has particular reference to an improved machine for taking the headed grain from a stack and delivering the same to the conveyer of a threshing machine feeder.

15 In threshing headed grain it is usually necessary to employ a number of men for the purpose of pitching the grain from the stack to the conveyer of the threshing machine feeder.

20 My invention has for its object to produce a simple and improved machine operable in connection with the feeder conveyer, whereby the grain will be taken from the stack and delivered to the said conveyer. As the 25 improved machine replaces the men employed for pitching the grain, the said machine may be appropriately called a pitching machine.

A further object of the invention is to 30 simplify and improve the construction and arrangement of parts entering into the construction of the said pitching machine.

With these and other ends in view which 35 will readily appear as the nature of the invention is better understood, the same consists in the improved construction and novel arrangement and combination of parts which will be hereinafter fully described and particularly pointed out in the claims.

40 In the accompanying drawings has been illustrated a simple and preferred form of the invention, it being, however, understood that no limitation is necessarily made to the precise structural details therein exhibited, 45 but that changes, alterations and modifications within the scope of the claims may be resorted to when desired.

In the drawing:-

Figure 1 is a top plan view of the machine.

Fig. 2 is a side elevation showing the machine arranged on top of a stack in position for operation.

Fig. 3 is a longitudinal sectional view 55 showing the machine positioned near the

bottom of the stack after having disposed of a portion of the stack.

Fig. 4 is a transverse sectional view taken on the line 4—4 in Fig. 3.

Fig. 5 is a transverse sectional view taken 60 on the line 5—5 in Fig. 3.

Fig. 6 is a sectional detail view taken on the line 6—6 in Fig. 1.

Fig. 7 is a detail side view of a portion of the machine illustrating a slight modification. 65

Fig. 8 is a detail view showing a modified construction of the hood or guide member.

Corresponding parts in the several figures are denoted by like characters of reference. 70

The improved machine comprises a main frame or conveyer frame 15 and an auxiliary frame or elevator frame 16, the latter being hingedly mounted on a shaft 17 which is supported for rotation in the side members 75 of the main frame adjacent to the discharge end of the latter. The main frame 15 supports two transverse shafts 18, 19 over which an endless conveyer apron 20 is trained. The conveyer apron 20 is equipped with transverse slats 21, the ends of the slats being provided with knives or cutting members 22 which are disposed substantially at right angles to the slats and to the surface of the apron. The slats 21 are also provided with 85 teeth or spikes 23.

Supported for rotation in the side members of the frame 15 near the receiving end of the latter is the shaft 24 carrying a spiked roller 25, said shaft being slightly spaced 90 from the shaft 19 over which the conveyer 20 is trained, and arranged to receive motion from the said shaft 19 through the medium of intermeshing gears 26, 27. Supported between the side members of the frame in the 95 interspace between the shafts 19 and 24 is a guide member consisting of an arcuate hood 28 which may be provided with slots 29 for the passage of the teeth 23 as well as of the spikes 30 with which the roller 25 is 100 equipped.

The auxiliary frame 16 is supported near its discharge end on a shaft 31 extending alongside the threshing machine feeder which is indicated at 32, said shaft 31 being 105 supported adjacent to the ends thereof so as to be unobstructed intermediate the ends. The shaft 31 may be driven by bevel gearing 33 from any convenient source of power. The shaft 31 is of non-circular cross section, 110

2
and it supports a roller 34 which is confined between the side members of the frame 16, which latter is slidably along the shaft 31. An endless conveyer apron 35 is trained over 5 the roller 34 and over the shaft 17 on which the frame 16 is hingedly supported. The conveyer apron 35 is provided with transverse slats 36 having teeth or spikes 37.

Supported for rotation in the side members of the frame 15 intermediate the shafts 17 and 18 is a shaft 38 carrying a roller 39 which is provided with annular grooves 40 for the passage of the teeth 23 and 37. The shafts 17, 18 are equipped with spur wheels 15 41, 42, each meshing with an idle spur wheel 43 which latter also meshes with a pinion 44 on the roller carrying shaft 38. The main frame 15 is supported by means of ropes 45 and tackle 46 from a derrick arm or boom 20 47, by means of which the said frame may be raised and lowered and its position shifted, it being obvious that the frame may be disconnected from the derrick when the machine is in actual operation.

25 In Fig. 7 of the drawings there has been shown a slightly modified arrangement for the transmission of motion between the conveyers 35 and 20 and under which the shafts 17 and 18, as well as the roller carrying shaft 38, are each provided with sprocket wheels 48, 49 and 50 over which a chain 51 is trained, thereby transmitting motion in the proper direction between the moving parts.

30 In Fig. 8 of the drawings there has been shown a slightly modified construction under 35 which the hood 28 is replaced by a plurality of curved tooth members 53 consisting of suitably supported and spaced arcuate rods or wires which will constitute a guide that 40 will operate in substantially the same manner as the hood 28 to guide the headed grain on to the conveyer apron 20.

45 In the operation of this device it will be understood that the pitching machine may be regarded as constituting an attachment to the threshing machine feeder or rather to the feeder conveyer which is indicated at 32 in the drawings, the shaft 31 being supported in bearings mounted on the trough or frame structure of the feeder conveyer. 50 It will be understood that the frames 15 and 16 are flexibly joined together, enabling the frame 15 to be lifted so that it may be placed on top of a stack of grain adjacent to one end of said stack. When the frame 15 is thus supported the frame 16 will project downwardly therefrom in an inclined position and will remain connected with the conveyer feeder. When the shaft 31 is rotated 55 it will set in motion the conveyer apron 35, and motion will be transmitted from the shaft 17 over which said apron is trained to the shaft 18 over which the conveyer apron 20 is trained, imparting motion 60 to the latter. The headed grain will be

engaged by the spiked slats on the lower lead of the conveyer 20 and will be moved along toward the receiving end of said conveyer, the blades 22 serving to cut into the grain to such an extent as to facilitate the 70 operation very materially. When the grain reaches the receiving end of the conveyer 20 it will be moved upwardly by the conjoint action of the spiked slats 21, the spiked roller 25 and the guide member consisting 75 of the hood 28 or equivalent device, the grain being deposited on the top lead of the conveyer 20 and carried thereby to the conveyer apron 35 and thence to the feeder conveyer on which it will be discharged. 80 As the operation progresses, the stack or that portion thereof which is engaged by the pitching machine becomes reduced in height, and the main frame 15 will gradually descend, gradually altering the disposition of the frame 16, which latter from a downwardly inclined position will gradually assume a horizontal and later on an upwardly inclined position with respect to the main frame 15. The operation, how- 85 ever, will continue without interruption until the main frame 15 reaches or almost reaches the ground, when it becomes necessary to use the hoisting apparatus for elevating the said main frame and supporting 90 it on the top portion of the stack. The operation is repeated as often as may be necessary to consume the stack.

95 It is obvious that during the progress of the operation that end of the frame 16 which 100 is connected with the frame 15 moves in an arc and that consequently a longitudinal movement will be imparted to the main frame 15. It is found, however, in actual practice that this movement does not materially impair successful operation of the machine, the parts being so constructed and proportioned that such longitudinal movement of the main frame may be regarded as negligible.

105 Having thus described the invention, what is claimed as new, is:—

1. In a machine of the class described, a main frame having shafts over which the conveyer apron is trained, said apron having transverse slats provided with spikes and with angularly disposed blades, an auxiliary frame hingedly connected with the main frame, an endless conveyer in said auxiliary frame, the receiving end of said auxiliary conveyer being spaced from the discharge end of the main conveyer, means for driving the conveyers, and a driven roller bridging the space between the two conveyers, said roller being provided with annular grooves for the passage of the spikes and blades of the main conveyer.

110 2. In a machine of the class described, a main frame having shafts over which the conveyer apron is trained, said apron hav- 115

ing transverse slats provided with spikes and with angularly disposed blades, an auxiliary frame hingedly connected with the main frame, an endless conveyer in said auxiliary frame, the receiving end of said auxiliary conveyer being spaced from the discharge end of the main conveyer, means for driving the conveyers, and a driven roller bridging the space between the two conveyers, said roller being provided with annular grooves for the passage of the spikes and blades of the main conveyer; in combination with means adjacent to the receiving end of the main conveyer for transferring material fed by the bottom lead of the main conveyer to the top lead of said conveyer.

3. In a machine of the class described, a main frame having shafts over which a conveyer apron is trained, said apron having transverse slats provided with spikes and with angularly disposed blades, and means for driving said conveyer, in combination with a curved guide member supported ad-

jacent to the receiving end of the conveyer, 25 a spiked roller supported for rotation in the frame in slightly spaced relation to the receiving end of the conveyer, and means for driving the spiked roller.

4. In a machine of the class described, a 30 main frame having shafts over which an endless conveyer is trained, said conveyer having slats provided with spikes and with angularly disposed cutting blades at the ends thereof, a spiked roller supported in 35 spaced relation to the receiving end of the conveyer, and a curved guide member supported in the interspace between the spiked roller and the receiving end of the conveyer, said guide member terminally over- 40 hanging the upper and lower leads of the conveyer.

In testimony whereof I affix my signature.

THOMAS W. PATTERSON.
